E. W. Turner:

— INVENTOR.

BY
Geo. P. Kimmel.
ATTORNEY.

UNITED STATES PATENT OFFICE.

EARL W. TURNER, OF KOKOMO, INDIANA.

FOOT ACCELERATOR.

Application filed December 19, 1921. Serial No. 523,470.

To all whom it may concern:

Be it known that I, EARL W. TURNER, a citizen of the United States, residing at Kokomo, in the county of Howard and State 5 of Indiana, have invented certain new and useful Improvements in Foot Accelerators, of which the following is a specification.

This invention relates to foot accelerators for motor vehicles and the embodiment 10 shown is primarily designed for use on Ford automobiles.

The object of the invention is to provide an accelerator which may be readily applied to the new style arms in present use on the 15 latest models of the Ford car carburetor which arms are now in the form of a thin metal stamping.

Another object of the invention is to provide an accelerator of the character specified 20 which may be readily installed by the operator of the car without the need of the services of an experienced mechanic.

With these and other objects in view, the invention consists in certain novel features 25 of construction as hereinafter shown, described and claimed.

In the accompanying drawings:—

Figure 1 represents a fragmentary top 30 plan view of an automobile showing this improved accelerator applied.

Fig. 2 is an enlarged plan view of a Ford car carburetor showing this improved accelerator applied, and

Fig. 3 is a side elevation of the carburetor 35 with the accelerator applied.

In the embodiment illustrated, an automobile A is shown having the usual engine E equipped with the ordinary carburetor C, the upright throttle valve stem S of which is 40 equipped with the usual throttle lever L movable in a horizontal plane and having in the free end of its longer arm an eye which usually receives the downturned end r of the hand actuated valve operating rod R whose 45 control member is positioned contiguous to the steering wheel W. The lever L which is in the form of a bell crank or L-shaped lever has its shorter arm equipped with the usual set screw s adapted to abut a stop s' on the 50 carburetor C to limit the movement of said lever.

All of the parts so far briefly described are of common construction the end r of the rod R being usually received in the eye of 55 the free end of the long arm of lever whereby endwise shifting of said rod by the oper-

ator will adjust the throttle valve to properly turn its stem S. When using the accelerator constituting this invention the end r of the rod R is removed from the eye of lever L 60 and is received in an arcuate slot 2 in a quadrant plate 1 constituting a part of the invention as will be hereinafter more fully described, without necessitating any change being made in rod R. 65

The accelerator constituting this invention comprises the quadrant 1 in the form of a one-piece stamping shown clearly in Fig. 2 which has an arcuate slot 2 formed therein to receive the downturned end r of the rod R. This quadrant 1 has an arm 3 extending obliquely downward and inwardly from its outer corner in a plane below the quadrant being connected therewith by a depending right angular extension 3a the arm and extension being preferably made integral with plate 1. The arm 3 is designed to overlie the long arm of the lever L and is provided at its free end with two laterally extending bendable fingers 4 which are bent down 75 under the lever as is shown clearly in Figs. 2 and 3. The outer end of arm 3 has an aperture for the reception of a bolt 5 which passes therethrough and through the outer terminal of the butterfly valve arm or 80 throttle lever L. The rear or inner end of the quadrant 1 is provided with an inwardly and laterally extending apertured gear 6 to receive a downturned end 7 of the foot accelerator rod 8. This rod 8 extends rearwardly through the floor F of the car and is equipped with an enlarged head 9 which constitutes a foot engaging member whereby the quadrant is actuated to control lever L 90 for opening the butterfly valve or throttle. 95

A coiled spring 10 is mounted on rod 8 between the head 9 and the floor of the car and exerts its tension to normally retain the stop screw s in contact with the stop screw s' to hold the lever L in the position in which 100 the throttle valve is partially closed as it normally stands.

In the use of this accelerator the forward movement of rod 8 by engagement of the operator's foot with the head 9 thereof will 105 swing the quadrant 1 outwardly turning the lever L so as to open the throttle valve the desired amount.

From the above description it will be obvious that the mounting of the downturned end r of the throttle rod R in the arcuate slot 2 of the quadrant 1 permits said quad-

rant to be actuated by the foot rod 8 without in any way affecting the hand controlled rod which will remain stationary during the operation of the accelerator.

5 It is of course understood that the throttle or butterfly valve may be opened to the desired extent by pressure on the head 9 of rod 8 and that when said rod is released the spring 10 will retract it and the quadrant 10 close the butterfly valve.

If the operator desires to use the hand operated throttle mechanism he may do so in the usual manner.

The preferred embodiment of the invention is disclosed in the drawings and set forth in the specification, but it will be understood that any modifications within the scope of the claimed invention may be made in the construction without departing from 20 the principle of the invention or sacrificing any of its advantages.

I claim:

1. A foot accelerator for automobiles, comprising a quadrant shaped plate having an arcuate slot therein to receive the hand controlled throttle rod of a carburetor, an extension depending from one end of said plate, an arm extending at an angle with respect to the plate and connected at 30 its outer end to said extension and further having its inner end provided with a plurality of fingers for overlapping the throttle lever of the carburetor, means for securing the outer end of said arm to the throttle lever of the carburetor, and said arm provided with means for the reception of the foot actuated operating rod of the carburetor.

2. A foot accelerator for automobiles comprising an arm adapted to be adapted to be seated upon and having means for overlapping the elongated legs of the throttle lever of a carburetor, means for securing the outer end of said arm to the said 45 leg, a vertical extension at the outer end of said arm, and a plate projecting from said

extension and provided with an arcuate slot for the reception of the hand controlled throttle rod of a carburetor and further having means at one side of the slot for 50 the reception of a foot actuated operating rod of the carburetor.

3. A foot accelerator for automobiles comprising an arm adapted to be positioned on the upper face of the elongated leg of 55 the throttle lever of a carburetor and further provided at its inner end with fingers adapted to overlap said leg whereby the inner end of the arm is secured to the leg, means for securing the outer end of the arm 60 to said leg, a vertical extension carried by the outer end of the arm, and a plate disposed at right angles with respect to said extension and provided with an arcuate slot for the reception of the hand controlled 65 throttle rod of a carburetor and further having one end provided with means arranged at one side of said slot for the reception of a foot actuated throttle rod of the carburetor.

4. A foot accelerator for automobiles comprising an arm adapted to be positioned on one of the legs of a throttle lever of a carburetor and having its inner end provided with bendable fingers for overlapping 75 said leg whereby the inner end of the arm is connected to the leg, means for securing the outer end of the arm to said leg, an extension projecting upwardly from said arm, and a quadrant shaped plate projecting at an angle with respect to said extension, and provided with an arcuate slot for the reception of the hand controlled throttle rod of the carburetor and further provided at one end and to one side of said 80 slot with means for the reception of the foot actuated throttle controlling rod of the carburetor.

In testimony whereof, I affix my signature hereto.

EARL W. TURNER.
